James S. Sheafe
BY Wm. N. Bates

ATTORNEY

UNITED STATES PATENT OFFICE.

JAMES SMITH SHEAFFE, OF CHICAGO, ILLINOIS.

BRAKE-SHOE.

No. 880,584.

Specification of Letters Patent.

Patented March 3, 1908.

Application filed November 2, 1907. Serial No. 400,358.

To all whom it may concern:

Be it known that I, JAMES SMITH SHEAFFE, a citizen of the United States, residing at Chicago, in the county of Cook and State of Illinois, have invented certain new and useful Improvements in Brake-Shoes, of which the following is a specification.

My invention relates to brake shoes as applied to locomotives and cars to simplify and improve the construction over the prior state of the art, and the object of my invention is the utilization of what is known as scrap brake shoes, *i. e.* those which are worn out and thereby rendered useless. This I accomplish by the means illustrated in the accompanying drawings, that is, by fastening the scrap shoe to a new shoe hereinafter described, the former wearing out completely before the new shoe begins to wear, thus putting to use all of the shoe, instead of being compelled to otherwise dispose of the scrap shoe.

Referring to the drawings; Figure 1 is a longitudinal view of the scrap shoe F fastened to the new shoe E. Fig. 2 is a plan view of shoe E, showing the face of said shoe. Fig. 3, is a cross section of shoes E & F, on the line A, B, Fig. 1, showing the method of locking the two shoes together. Fig. 4, is a longitudinal view of a driver brake shoe illustrating the same principle described in the car shoe, the recess H' carrying a lug with which the scrap shoe is provided similar to C'. Fig. 5, is a plan view of the new shoe provided with two countersunk cored holes M, and Fig. 6, is a view showing a round steel strengthening rod in connection with the plate O.

H is a recess cored in the face of shoe E for the purpose of carrying a lug similar to C on the back of another shoe; and G are recesses cored in the face of the shoe E at both ends to carry lugs, similar to B, upon the back of the other shoe.

Fig. 3 is a cross section of shoes E and F on the line A—B, Fig. 1, showing my method of locking the two shoes together. A bolt J passes through the hole R in the shoe E, and a hole corresponding to P in the central lug of the shoe F, similar to C. This bolt is held secure by means of a cotter key K or by a nut, or any other suitable fastening means. In this figure, O designates the steel plate as shown and extends to the face of the shoe as at z, thereby greatly strengthening the lug.

The mechanism shown in Figs. 1, 2, and 3

as above described is that of the brake shoe as applied to cars. In Figs. 4 and 5 are views of the shoe applied to locomotive drivers, and in these figures the "blind driver shoe" 60 is shown, although the same general principle can be applied to what is known as the flange shoe, which is precisely the same as that applied to the car shoe above described.

As the ordinary driver brake shoe has two flanges upon its face in order to guide it and keep it in place on the wheel, the back of my driver brake shoe must be cored out sufficiently to allow said flanges (with which my shoe is also provided) on the face of a new 65 shoe to fit upon the back of the old or scrap shoe, the recess so formed, to be of any size, is to lighten the shoe or just large enough to permit of interlocking. The structure of the driver brake shoe is to be of the usual 70 construction with the exception of the part for the purpose of strengthening the shoe 75 when it has worn thin.

The method of strengthening the shoe is illustrated by the mechanism shown in Fig. 80 6 of the drawings. N is a round, square, triangular or other shaped steel rod of such thickness as to allow of sufficient strength and bent substantially in elliptical form for the purposes intended, it being hooked at both 85 ends, it allows of an interchangeable use either of these ends being available to support the shoe upon the brake head, together with the bolts which are used in holes M. O designates a steel plate suitably shaped 90 and punched to reinforce the lug C' with which the back of the shoe is provided, and passes under both sides of the elliptical rod N, thus preventing the locking bolt tearing away from the lug. Both the elliptical 95 shaped rod and plate O are embedded within the body of the shoe as clearly shown in Fig. 5 for the purpose of reinforcing it. The shoe is made solid by means of pouring molten iron around said elliptical wire N and plate O. 100

Having thus described my invention, what I claim and desire to secure by Letters Patent, is:

1. A brake shoe having a lug centrally and integrally located on the back of said shoe, 105 the lug having a longitudinal opening thereto and a horizontal perforation therein, said perforation located upon a middle transverse line for the reception of a bolt, a keeper securing said bolt, the bolt being projected 110 through the perforation in said lug; in combination with end lugs fitting into corre-

sponding recesses in the face of the shoe, thus preventing the displacement of the shoe either in a vertical or lateral direction.

2. A brake shoe of the character described, 5 having a lug formed centrally and integrally on the back of the shoe, and having a perforation therein for the reception of a bolt, a keeper securing said bolt, the bolt being projected horizontally through the perforation in said 10 lug, and lugs fitting in corresponding recesses in the face of the shoe; in combination with reinforcing plates located in each shoe, thus strengthening the same and providing a suitable foundation for the bolt, thereby pre-

venting the lug from giving way and tearing 15 out.

3. A brake shoe composed of a back and face portion, having counter sunk cored holes therein and lugs on said shoe, recesses formed in the shoe to receive the lugs, in 20 combination with the substantially elliptical strengthening rod.

In testimony whereof I affix my signature, in presence of two witnesses.

JAMES SMITH SHEAFE.
